UNITED STATES PATENT OFFICE.

JOHN VINCENT PAUL, OF VERDUN, QUEBEC, AND CHARLES ALAN NORTON, OF SUNNY BRAE, NEW BRUNSWICK, CANADA.

EXHAUST SPREADER FOR LOCOMOTIVE ENGINES.

Application filed September 13, 1922. Serial No. 588,018.

To all whom it may concern:

Be it known that we, JOHN VINCENT PAUL, a citizen of the United States, residing at 579A La Salle Road, Verdun, in the 5 Providence of Quebec, Dominion of Canada, and CHARLES ALAN NORTON, a subject of the King of Great Britain, residing in the town of Sunny Brae, in the county of Westmoreland, in the Province of New Brunswick, 10 Dominion of Canada, have invented certain new and useful Improvements in Exhaust Spreaders for Locomotive Engines, of which the following is a specification.

This invention relates to improvements in 15 exhaust spreaders for locomotive engines, and the objects of the invention are to effect a reduction in back pressure in the cylinders of the same which will result in an increased efficiency of the engine enabling 20 it to haul greater tonnage without any increase in boiler power, or to handle the same tonnage with marked reduction in fuel used, or a combination of these.

Further objects are to provide such a device as may be readily applied to the present locomotive front end arrangement and the present design of cylinders etc.

More particular objects of the invention are to increase the rubbing surface between 30 the jet of exhaust steam and the stack gases.

Further objects still are generally to improve and simplify the construction of the device to better adapt it to perform the functions required of it, and the invention consists essentially of the improved construction and arrangement of parts hereinafter described in detail in the accompanying specification and drawings.

40 In the drawings:

Figure 1 is a sectional elevation of the exhaust pipe and spreader and a portion of the stack extension for a locomotive.

Figure 2 is a sectional elevation of the 45 spreader turned at right angles to Figure 1.

Figure 3 is a plan view of the parts shown in Figure 2.

In the drawings, like characters of reference indicate corresponding parts in all the 50 figures.

Referring to the drawings, A indicates the exhaust pipe, B the stack extension and C the spreader. The exhaust pipe A is constructed of any suitable material such as cast 55 iron or steel and is of inverted frustro coni-

cal shape having a base flange 10 formed with bolt holes 11 by which it may be secured in position, as shown on the cylinder saddle, the exhaust pipe being as usual provided with a central transverse bridge wall 60 12. The sides of the exhaust pipe may be straight or tapered, circular, square or of any other shape which will conform to and end in the top opening which opening may be made circular, square, oval, elliptical or 65 any other shape that may be found most convenient. A short distance from the top, the exhaust pipe projects through and is secured to the horizontal dead or draft plates D, the connection in the embodiment illustrated being effected through an annular flange 13 on the exhaust pipe, which is connected by bolts 14 with the plates. The distance the exhaust pipe extends above the plates depends upon the results obtained 70 from tests and may be adjusted to suit the condition of the type of engine with which it is employed.

The spreader C may be of any suitable material such as cast iron or steel and is designed to spread the exhaust jet from the centre outwardly, to which end it is constructed of inverted conoidal shape having a plurality of ports or passages 15 for the exhaust steam. In Figures 1 to 3, a plurality 80 of openings 15 are provided extending radially. By the formation of the exhaust opening in the plurality of ports 15, as in Figures 1 to 3, the perimeter or rubbing surface of the jet is still further increased. The 85 spreader should be of such depth as to extend close to the centre bridge wall 12 or it may be of lesser depth as conditions warrant and experience proves most satisfactory, but the depth should be such as to give as little 90 interference or obstruction to the exhaust jet as is possible so that the jet as it comes from the cavities in the cylinder saddle may meet with as little interference or obstruction as possible, and be gradually and uniformly spread until it passes through the 95 ports 15.

It will be observed that between the ports 15 there are blank areas 17 on the head of the spreader through which no steam will 100 pass and which provide a means whereby the front end gases may circulate around the exhaust jets as they issue from the ports 15.

The number and size of the ports 15 and 110

2
areas 17 should be so arranged that the spaces between the exhaust jets may be as large as possible and such that will prevent as far as possible the tendency of the jets to close together before a reasonable distance has been covered, a condition which, if permitted, would reduce the area of the rubbing surface.

5 The spreader C may be supported in position in any convenient way. In the form shown in Figures 1 to 3 the spreader is provided with lateral lugs 18 which fit over corresponding lugs 19 on the exhaust pipe A and the lugs are secured together by suitable 15 bolts 20.

It will be seen that the openings 15 extend substantially axially and opening against the conoidal surface of the spreader will offer a minimum resistance to the passage 20 of the exhaust steam. This conoidal surface is preferably concave slightly in cross section as indicated in Figure 1.

The stack extension B is of usual form and constructed of cast iron or steel extending 25 downwardly from the stack to a point on a line with or slightly above the top of the exhaust pipe A, the bottom portion being bellied out to make the diameter at the mouth from six to ten inches or thereabouts larger 30 than that of the diameter of the exhaust pipe A, whereby ample space will be provided for the front end gases to circulate around and become entrained with the exhaust jet as it issues from the pipe A.

35 The stack proper should be of such size that the jet completely fills the stack before it reaches the top.

It will be seen that in the invention the perimeter of the exhaust jet will be materially increased and as it is universally conceded that it is the frictional contact on the jet of the front end gases that creates a vacuum in the front end which in turn causes the draft through the fire, it follows 40 that the increase effected in the area of the rubbing surface will tend to increase the vacuum and thereby increase the draft. It will also be seen that by breaking up the exhaust jet from the centre advantage is 45 taken of the volume of steam at the centre of the jet that is doing no useful work and instead of merely forming it to escape to the atmosphere, it is expanded and caused to be effective in moving the stack or front end 50 gases. It may also be observed that the velocity of the jet at the centre which is thus taken advantage of is from two to three times the velocity at the outer surface. The increase in area of the exhaust jet will result in 55 a reduction of back pressure in the cylinders 60

with a corresponding increase in power to the locomotive. It further follows that this increase in draft will further combustion and cause more oxygen to be drawn into the fire box together with the increase in draft and reduction of back pressure or the combination of both will cause a more economical operation of the locomotive, thereby effecting a marked saving of fuel besides increase of power.

As many changes could be made in the above construction and many widely different embodiments of our invention within the scope of the claims, constructed without departing from the spirit or scope thereof, it is intended that all matter contained in the accompanying specification and drawings shall be interpreted as illustrative and not in a limiting sense.

70 What we claim as our invention is:

1. An exhaust steam spreader for locomotive engines comprising an exhaust pipe, a bridge wall, a conical spreading member extending from above the bridge having its peripheral edge fitting snugly against the wall of the exhaust pipe, the conical surface of the spreader being concave in cross section, the spreader being formed with a plurality of radiating ports, each port increasing in width from the centre outwardly, a pair of ears on the exhaust pipe, and lugs 80 on the spreader engaging the ears.

2. An exhaust steam spreader for locomotive engines, comprising an exhaust pipe having a base flange and an outwardly projecting flange a distance therefrom, and to which the draft plates of the locomotive may be secured, a bridge wall, a conical spreading member extending from above the bridge having its peripheral edge fitting 95 snugly against the wall of the exhaust pipe, the conical surface of the spreader being concave in cross section, the spreader being formed with a plurality of radiating ports, each port increasing in width from the centre outwardly, a pair of ears on the exhaust pipe, lugs on the spreader engaging the ears, and fastening means engaging the ears and lugs.

90 In witness whereof we have hereunto set 110 our hands in the presence of witnesses.

JOHN VINCENT PAUL.
CHARLES ALAN NORTON.
